UNITED STATES PATENT OFFICE.

WILLIAM F. PACKARD, OF BROCKTON, MASSACHUSETTS, ASSIGNEE OF ONE-HALF TO
KENO SUPPLY COMPANY, OF BROCKTON, MASSACHUSETTS, A CORPORATION OF
MASSACHUSETTS.

APPARATUS FOR FILLING SHOES.

1,201,087.

Specification of Letters Patent. Patented Oct. 10, 1916.

Application filed June 20, 1913. Serial No. 774,841.

To all whom it may concern:

Be it known that I, WILLIAM F. PACKARD, a citizen of the United States, residing at Brockton, in the county of Plymouth and State of Massachusetts, have invented a new and useful Apparatus for Filling Shoes, of which the following is a specification, reference being had therein to the accompanying drawings.

10 This invention relates to an apparatus for treating and applying filler material to shoes.

In the manufacture of welt shoes a cavity is formed between the inner and outer soles 15 which cavity it is customary to fill with a suitable material in order to give the sole thickness and stability. Various substances and compositions have been and are employed for this purpose and one such composition is described in United States Letters Patent No. 1,019,964 issued to James P. Keener, March 12, 1912. In a shoe filler of this particular character the material which is normally more or less solid is reduced to a plastic condition by heat and in that condition is applied to the shoes by a knife or spreader.

The main object of my invention is to provide an apparatus for filling shoes in 30 which the filler is maintained in a suitable condition for application and by the use of which it may be applied to shoes with rapidity and with a minimum amount of labor.

35 A further object is to provide an apparatus which is of low cost both as regards construction and operation and which is compact and efficient.

Other objects of the invention will be 40 more specifically set forth and described hereinafter.

In the accompanying drawings illustrating the preferred form of my invention Figure 1 is a side elevation partly in vertical section of an apparatus constructed and operated in accordance with my invention; Fig. 2 is a plan view of the same and Fig. 3 is an elevation of the front portion of the kettle.

50 In the illustrated embodiment of the invention is shown a steam-jacketed kettle 4 of any suitable form, supported upon legs 5. The kettle may be connected to a suitable source of steam by an inlet pipe 6 entering the upper part of the kettle. The steam

flows through the chamber 7 and through an outlet pipe 8 controlled by a valve 9 and thereby maintains the kettle at a high temperature. The inlet pipe is preferably bent to form an open loop 10 lying in a horizontal plane and serving as a support for a receptacle 11 which is adapted to hold a surplus supply of filler material from which the kettle may be replenished from time to time.

65 A portion 12 of the exterior surface of the kettle may be finished flat so that the operator may after the shoe has been filled draw it upwardly against the flat surface to smooth it. The flat surface is arranged on 70 that side of the kettle which is at the operator's left hand when he faces the apparatus. On the opposite side, the kettle may be provided with suitable means for holding the knives or spreaders used in applying the filler material. The means shown in the drawings comprises a plate 13 attached to the side of the kettle by bolts or screws 14 and provided with a series of vertical grooves 15 open at the top to receive the blades of the knives or spreaders 16.

75 In the use of my apparatus the kettle 4 is connected to a suitable steam supply which flows through the inlet pipe 6 into 80 the chamber 7 and out through the outlet pipe 8 thereby heating the kettle. The temperature of the kettle may be regulated within certain limits by the valve 9 which controls the flow of steam. After the kettle has become heated, it is then partially 85 filled with the filler material which is reduced by the heat to a plastic condition suitable for application to shoes. At the same time the receptacle 11 is loaded with filler 90 material 17 which is gradually heated by the coil 10 so that when the kettle is replenished therefrom, the filler is of such temperature that it may be mixed with that in the kettle without retarding the work. As the work 100 progresses the receptacle is filled from time to time with fresh material.

105 When working the operator takes a position in front of the kettle with a knife or spreader in his right hand and a shoe bottom uppermost in his left hand. Holding the shoe over the kettle he takes up the filler material on the knife or spreader and fills in the shoe bottom leveling it off with the spreader. The filled shoe is then drawn 110

over the exterior finished portion of the kettle with the top surface of the filler in contact therewith to smooth the filler. In drawing the shoe over the part 12 it is essential that it be held with the toe pointing downwardly and be drawn upwardly in order that the filler material may be held in the toe portion. If the shoe be drawn in the opposite direction the filler material is crowded or drawn away from the toe leaving a partially filled sole.

It will be noticed that my apparatus is so arranged that the knives or spreaders are on the right hand side as the operator stands 15 in position in front of the kettle and the finished portion 12 on the left hand side. This arrangement permits the operator to use his right hand in filling the shoe held in his left hand and after the shoe is filled to 20 draw it upwardly over the finished portion of the kettle with his left hand before placing the shoe in the finished pile. This conduces to rapidity and economy of labor because all unnecessary and superfluous movements are eliminated and the operation of applying the filler material is reduced to 25 its lowest terms.

It is to be understood that my invention may be embodied in other constructions 30 than that hereinbefore described and illustrated.

What I claim is:

1. An apparatus for filling shoes comprising a steam-jacketed kettle for reducing the 35 filler to a plastic state, an inlet pipe for delivering steam to said kettle, a valve for controlling the passage of said steam from the kettle, a receptacle for filler material so arranged as to be supported on and heated by said inlet pipe, an integral upright portion of the kettle being finished flat to provide means for smoothing the filler off after it has been applied to the shoe and means disposed on the opposite side from 40 the flat portion for containing the tools for filling the shoes with filler material.

2. An apparatus for filling shoes comprising a kettle unobstructed over its upper surface to present an approximately horizontally disposed exposed opening or mouth 50 enabling an operator to work thereover and have direct access thereto, a receptacle arranged above and offset from the vertical plane of said opening or mouth portion of the kettle to occupy a position laterally therebeyond, said receptacle being open at that side which faces the kettle to discharge 55 toward the operator, the bottom thereof occupying approximately the plane of the edge of the kettle bordering the opening or mouth to permit the operator to push the material from the receptacle into the kettle, substantially as described.

3. An apparatus for filling shoes comprising a kettle unobstructed over its upper surface to present an approximately horizontally disposed exposed opening or mouth enabling an operator to work thereover and have direct access thereto, a receptacle arranged above and offset from the vertical plane of said opening or mouth portion of the kettle to occupy a position laterally therebeyond, said receptacle being open at that side which faces the kettle to discharge 65 toward the operator, the bottom thereof occupying approximately the plane of the edge of the kettle bordering the opening or mouth to permit the operator to push the material from the receptacle into the kettle, the kettle and the receptacle being formed integral and 70 adapted to be heated, substantially as described.

4. An apparatus for filling shoes comprising a kettle, a receptacle arranged above and offset from the kettle to occupy a position beyond the edge of the kettle, said receptacle being open at that edge which faces the kettle, the bottom thereof occupying 75 approximately the plane of the top of the kettle to permit the operator to discharge the material from the receptacle directly into the kettle, and means for heating the kettle and the receptacle, said means comprising in part a conducting pipe for heating medium elongated and bent laterally to 80 embrace a wide area beneath the receptacle, substantially as described.

5. An apparatus for filling shoes comprising a kettle, the surrounding wall of which is formed to receive a heating medium, an upright portion of the exterior surface of 85 said wall being finished and flat for smoothing the surface of the filler after it has been applied to the shoe, said finished flat surface constituting a part of the inclosure for 90 the heating medium so as to be directly heated by the latter.

6. An apparatus for filling shoes comprising a steam-jacketed kettle, a portion of the outer wall of the steam-jacket being finished 95 to constitute a smoothing device for the surface of the filler after it has been applied to the shoe, the hollow interior of the steam-jacket extending over the interior of said finished portion to enable the heating medium 100 to directly heat said finished portion, substantially as described.

In testimony whereof, I hereunto set my hand in the presence of two subscribing witnesses, this the eleventh day of June, 120 1913.

WILLIAM F. PACKARD.
